UNITED STATES PATENT OFFICE.

CHARLES J. HARTLEY, OF DECATUR, ILLINOIS, ASSIGNOR TO JOHN K. WARREN AND BRADFORD K. DURFEE, BOTH OF SAME PLACE.

ELEVATOR AND WEIGHING ATTACHMENT FOR THRASHERS.

SPECIFICATION forming part of Letters Patent No. 377,358, dated January 31, 1888.

Application filed May 17, 1887. Serial No. 238,491. (No model.)

To all whom it may concern:

Be it known that I, CHARLES J. HARTLEY, of the city of Decatur, county of Macon, and State of Illinois, have invented certain new and useful Improvements in Grain Elevating and Weighing Attachments for Thrashing-Machines, of which the following is a specification.

My invention relates, first, to the weighing mechanism; second, to means for adjustably connecting the elevator with the thrasher; third, to a hinge-joint in the elevator; fourth, to mechanism that permits the bucket-chain to be readily manipulated; fifth, to a conveyer 15 with an adjustable chute or valve that co-operates with the elevator and weighing mechanism and enables the grain to be discharged from either side of the thrasher, and, sixth, to universally-adjustable chutes that convey 20 the grain from the machine to wagons or other desirable place of deposit.

In the drawings accompanying and forming a part of this specification, Figure 1 is an elevation of my machine from an end of the 25 thrasher, the relative position of said thrasher being indicated by broken lines. Fig. 2 is a side elevation of a chute and a portion of the conveyer. Fig. 3 is a side elevation of a section of the elevator embodying the hinge-joint. Fig. 4 shows the upper portion of the elevator 30 swung on the hinge to occupy a horizontal position. Fig. 5 is a vertical section of the mechanism shown in Fig. 4. Fig. 6 is an inner face view of one side of the hinge. Fig. 35 7 indicates the general construction of the bucket-chain used in connection with my invention. Fig. 8 is a side view of the weighing mechanism as seen from across the thrasher. Fig. 9 is a diagram of the mechanism used to 40 adjustably connect the elevator with the thrasher. Fig. 10 is a detail drawing of a movable bearing for the lower shaft of the elevator. Fig. 11 is a view of that portion of the elevator shown in Fig. 3, from the right-hand 45 side of said figure. Fig. 12 is a central longitudinal section of a set of hinge-plates. Fig. 13 is a central vertical section of the support for the swinging chute.

The vertical elevator 1 is secured to the 50 thrasher by means of rods 45, which are longitudinally adjustable in sockets 49 on the

thrasher and in annular brackets 46 on the elevator. The sockets are secured to the thrasher by means of flanges 51, which may be perforated to admit screws or other securing devices. The annular brackets are integral with clamp-plates 13, and said plates are firmly secured to the elevator by bolts 48. Set-bolts 50 in the sockets and 47 in the brackets provide means for securing the rods 60 in any desired position of adjustment. Securing devices, as above described, are placed one at the top of the thrasher and one near the bottom of the elevator, and by their use the elevator may be readily placed and retained in a vertical position or parallel with the side of the thrasher.

At a point slightly above the top of the thrasher the elevator is provided with a hinge-joint, and said hinge is composed of two sets 70 of plates on opposite sides of the elevator-casing. The sets are horizontally coincident in all their parts, and are identical in the construction, with the exception of the variation that is necessary to enable them to be used in 75 opposite positions. Each set comprises a plate, 32, which is secured to the upper portion of the elevator, and a plate, 34, which is secured to the lower portion of the same. The plates are in the same vertical plane, with the exception of the overlapping ledge 38 and square portion 33 on plate 32, the inner surfaces of which are in approximately the same plane with the outer surface of the plates. The lower plate, 34, is perforated to form a bearing for shaft 37, and has an outwardly-projecting boss, 36, that forms a pivot for the larger perforated boss, 35, of the upper plate. On the inner side of each lower plate, arranged diagonally above and below the pivot in line 80 with the bucket-chain of the elevator, are projections 43 and 44, that sustain the chain in the manner indicated in Fig. 5 when the upper part of the elevator is laid down, and prevent disadjustment of both chain and buckets. 85 The flange 38 and the lower portion of square 33 overlap the lower plate when the elevator is erect, forming a substantial close joint, and when the upper portion of the elevator is laid down the square 33 fits over the corner of the 90 lower plate and terminates the motion of the said upper portion when a right angle has been 95 100

formed. The door 39 is hinged at 40, and is swung outward from below to permit the top of the elevator to be laid down.

The brace-rod 19 (shown in Fig. 1) holds the top of the elevator in an upright position, and it is assisted somewhat in the discharge of its function by the coincidence of the outer or back portion of the hinge-plates, which prevent motion away from the thrasher.

10 Grain carried up the elevator is discharged through chute 2 and hopper 3 and falls in one of the quadrantal compartments of the circular meter-frame 56, which is held against rotation by the scale-beam 59, which presses against the under side of the rectangular frame 58, which is securely attached to a face of the meter. When a quantity of grain sufficient to overbalance weight 63 has accumulated in a compartment, the meter-frame will 15 describe a quarter-revolution, discharging the grain and bringing another compartment in position to repeat the operation. The novel feature of this part of my invention comprises the peripheral segment 4, which incases the compartments as they fill and which is pivotally connected with the shaft of the meter-frame by radial bars 61. From the under side of the lower bar extends arm 62, which is provided with a roller that rests on 20 an inclined projection or conformation, 60, of the scale-beam, and that is substantially coincident with the corner of the rectangular frame that is in position to depress the scale-beam. While a compartment is filling the casing is 25 held in its shown position by the pressure of the scale-beam against arm 62. As the compartment rotates, the beam descends and removes the obstruction to the rotation of the casing, which moves with the said compartment until sufficient momentum is developed 30 to readily overcome the frictional pressure of the grain against the casing, when the end 64 strikes the hopper 5 at 65 and abruptly terminates the motion, so far as the casing is concerned, until the returning scale-beam presses 35 projection 60 against arm 62 and returns the casing to the position shown.

The partitions of the meter are indicated by dotted lines at 57. 66 is a bracket-bearing for the scale-beam. 6 is an inclined chute that is provided with valve 28. (Shown by dotted lines in Fig. 2.) This valve determines by its adjustment whether the grain shall be carried through conveyer 7 or be discharged directly 55 from the chute; or, in other words, it determines from which side of the thrasher the grain shall be discharged. Grain is carried through the conveyer by scrapers on belt 31, which is driven by pulley 30. The handle 27 of valve 28 has some elasticity, and a rack, 29, has recesses in which said handle presses at either termination of its throw with sufficient firmness to maintain a practical degree of rigidity in the adjustment of the valve.

60 Chute 10 is placed under valve 28, and chute 18 is placed at the opposite end of the con-

veyer. These chutes are identical in construction, and are each adjustably connected with the conveyer by means of pivoting-links 20 and revolving bands 24.

At each end of the conveyer is an annular band, 23, provided with a flange at its lower outer edge, on which band 24 rests and rotates. A downward extension, 26, of the rear portion of the band partly incases the upper end 75 of the chute and provides points of attachment for the links. At the rear of the band is a vertical ratchet-bar, 21, and on the under surface of the upper end of the chute is a pawl-plate, 22, that engages the teeth of the ratchet-bar.

To adjust the chute horizontally, it is only necessary to swing it around on its vertical pivot. To adjust it vertically, force must be exerted in the direction of its length until the 85 pawl becomes disengaged from the ratchet-bar, when the outer end may be raised or lowered and the pawl be again permitted to engage the ratchet-bar at the desired position. The oblique position of the links causes the chutes 90 to press against the ratchet-bars in a vain endeavor to swing under their points of suspension, and the pressure so developed is utilized to increase the permanency of the various positions of vertical adjustment in the chutes. 95 The lateral projections 25 prevent an undue displacement of the links while adjusting the vertical position of the chutes.

The lower outer portion of the elevator is in the form of a flap, 15, which is hinged at 17 100 and detachably secured by catches 16 of any suitable construction. The bearing 53 of the lower elevator-shaft is mounted on a sliding plate, 52, and has vertical motion in slot 54 of frame 14. When the bearing is in operative 105 position, it is held by bolt 55, which screws into the hole in the upper end of plate 52. Sliding bearings, as described, are placed one on each side of the elevator-casing, and a rod at 17, extending from frame to frame below 110 the elevator, provides a hinge for the flap. When it is necessary or desirable to manipulate the chain or buckets in any manner or for any purpose, the flap may be swung down to permit access and the bolts 55 be withdrawn 115 to produce slack in the chain.

Power is imparted to the elevator from the thrasher by means of chain 11. A set of gearing suitably mounted at 12 changes the direction of the motion and conveys it to the opposite side of the elevator. A chain connects 120 gearing 12 with the shaft 37 of the conveyer, which extends through the elevator, and a third chain connects the said shaft with sprocket-wheel 57 on the upper shaft of the elevator. 125 The conveyer has a belt-tightener at 9 and the elevator has a similar contrivance at 8.

The grain may be discharged from either side of the thrasher by a simple manipulation of the handle 27 of valve 28.

Preparatory to moving the thrasher the brace-rod is disconnected and the upper por-

tion of the elevator and the weighing mechanism is laid on the thrasher, as indicated by dotted lines in Fig. 1.

The universal coupling of the chutes enables 5 the grain to be discharged in various directions.

The swinging casing of the meter-frame makes greater accuracy attainable by delaying the resistance of the friction of the grain 10 until a degree of momentum sufficient to readily overcome it has been developed, whereas, if the casing were stationary, the resistance of the friction would oppose the initial motion of the meter, and a variation in the degree of 15 friction would perceptibly and injuriously affect the accuracy of the operation.

I claim as new and desire to secure by Letters Patent—

1. In grain-meters, in combination, a circular meter comprising a series of sector-formed compartments adapted to rotate intermittently in one direction, and a peripheral partial casing for said meter adapted to oscillate on the shaft thereof, as and for the purpose set forth. 25

2. In grain-meters, in combination, the circular meter divided into sector-formed compartments, the frame on the face of the meter having sides corresponding in number to the compartments of the meter, the scale-beam under the frame, and the peripheral partial casing resting on the scale-beam and pivoted on the shaft of the meter, as and for the purpose set forth.

3. In grain-meters, in combination, the circular meter divided into quadrantal compartments, the rectangular frame on a face of the meter, the scale-beam under the frame, the peripheral partial casing pivotally connected with the meter-shaft by the radial arms, the

arm on the lower bar resting on the scale-beam at a point coincident with a corner of the rectangular frame, and the inclined spur on the scale-beam, as and for the purpose set forth. 40

4. The hinge for an elevator, composed of plate 32, having the overlapping square portion 33 and the boss 35, and the plate 34, having the boss-formed pintle 36 and the inner projections, 43 44, in combination, as set forth. 45

5. The attaching device for elevators, comprising the clamp-plates 13, held on the elevator by bolts 48 and provided with annular brackets 46, sockets 49, adapted to be secured to the thrasher, rods 45 in the sockets and brackets, and set-screws 47 and 50, as and for the purpose set forth. 50

6. The chute secured to the band by the pivoting-links, the downwardly-extended ratchet-bar on the band, and the pawl-plate on the chute in contact with the ratchet-bar, all in combination, for the purpose set forth. 55

7. The revolving band, the chute secured to the same by the pivoting-links, the downwardly-extended ratchet-bar on the band, and the pawl-plate on the chute in contact with the ratchet-bar, all in combination, as and for 60 the purpose set forth.

8. The sliding bearing comprising the slotted frame 14, the plate 52, carrying the bearing and having the perforation in its upper end, and the adjusting-bolt 55 in the upper 70 portion of the frame, as and for the purpose set forth.

In testimony whereof I sign my name in the presence of two subscribing witnesses.

CHARLES J. HARTLEY.
